C. KUGEL.
ANNEALING FURNACE.
APPLICATION FILED SEPT. 20, 1913.
1,118,869. Patented Nov. 24, 1914.

UNITED STATES PATENT OFFICE.

CARL KUGEL, OF BRUNSWICK, GERMANY.

ANNEALING-FURNACE.

1,118,869.

Specification of Letters Patent. Patented Nov. 24, 1914.

Application filed September 20, 1913. Serial No. 790,868.

To all whom it may concern:

Be it known that I, CARL KUGEL, manufacturer, citizen of the Kingdom of Prussia, Empire of Germany, residing at Brunswick, 5 Germany, have invented certain new and useful Improvements in Annealing-Furnaces, of which the following is a specification.

The present invention has reference to 10 annealing furnaces, and it proposes certain hereinafter-described improvements in or relating to the cooling chambers of such furnaces, and their associated parts or adjuncts.

15 An embodiment of the invention is illustrated in the accompanying drawing, in which—

Figures 1 and 2 are, respectively, a vertical section and a plan view of the improved 20 furnace, the section being taken on line A—B—C, Fig. 2.

Referring more particularly to said drawing, the furnace is shown as comprising an annular cooling chamber *a*, which is open at 25 its top and bottom, and, beneath the same, a single charging chamber *f* and a single heating chamber *e* although no limitation to this number is contemplated, the chambers *e* and *f* having their upper ends communicating with chamber *a*. Upon the top of chamber *a* is mounted a rotatable cover *c*, to which a step-by-step movement may be imparted either by hand or by the aid of suitable mechanism, (not shown), in any desired 30 manner, the cover being formed at its inner and outer edges with depending flanges that project into oil-filled gutters *b* provided upon the corresponding upper edges of the walls of chamber *a*. Chamber *f* is provided 35 with a suitable door *x* which is removed therefrom during both the introduction of the charges and their withdrawal after having been annealed and cooled. The iron plates or other metal to be treated are deposited in skeleton frames *g*, a plurality of 40 which is made use of, and these frames are provided at their upper ends with lids *d* that form the covers for the chambers *e* and *f* and are adapted to be raised and lowered 45 within the chamber *a*, so as to lift the frames into the latter chamber from the said chambers *e* and *f*, and vice versa. The frames 50 may have any desired form, and each may consist, for example, of a base or bottom plate, to which two diametrically-opposite, vertical rods are attached, the upper ends of

said rods being connected to the lids *d*. In their lowered positions, the covers coating with the afore-mentioned chambers are designed to form gas-tight joints therewith. 55 Any desired means of mechanism may be utilized for effecting the movements just specified, that shown consisting of vertical racks *i*, which are attached at their lower ends to the covers and are operated through the agency of pinions *k* suitably mounted on cover *c*, the arrangement being such, therefore, that when any pinion is rotated, the rack associated therewith, and, in consequence, the frame and lid connected to that 60 rack, will be either raised or lowered, according to the direction of rotation.

The operation is obvious, and may be stated, briefly, as follows. An empty frame *g* is first brought above chamber *f* by the 65 rotation of cover *c*, and then lowered thereinto. The door *x* is removed from said chamber, the frame then charged with the plates or other metal, the door then replaced, and the said frame subsequently raised into 70 chamber *a*. Cover *c* is then rotated one step in a clockwise direction, (Fig. 2), thereby bringing a second empty frame above chamber *f* and advancing the previously-charged frame toward the heating chamber *e*. The 75 second frame is then successively lowered into chamber *f*, charged and returned to chamber *a*, in the manner already described, after which cover *c* is again rotated one 80 step as before. This second step again 85 brings an empty frame above chamber *f*, and it also brings the frame first charged above chamber *e*, the number of frames and the disposition of the said chambers *e* and *f* 90 relative to each other being arranged with 95 that object in view. The frames above said chambers are then lowered thereinto, the frame in the heating chamber remaining in the same sufficiently long to permit the annealing or other treatment to be completed. 100 During the remainder of its passage through chamber *a*, the frame containing the metal thus treated is gradually cooled, such action being increased by filling the central space defined by the inner wall of that chamber 105 with water or other suitable cooling medium, so that by the time that this frame ultimately returns to its original position above chamber *f*, the cooling operation will likewise have been completed. On reaching 110 such position, the frame is lowered into said chamber, emptied, and re-charged, after

which the same cycle of steps or treatments is repeated. Thus it will be seen that for each step through which cover *e* is turned, a charged frame will be brought above chamber *e*, and a second frame, whose contents have been completely treated, above chamber *f*, the latter frame being subsequently again charged and sent on its course through the furnace.

10 The charging and emptying of the frame *a* in the chamber *f* is readily effected, since the removal of the door *x* affords ample access to said chamber, the metal being easily stacked up upon or removed from the frame bottom plate, between the frame rods. If preferred, however, the frame may be detached bodily from its lid and withdrawn from the chamber *f*, both for charging and for emptying purposes, and subsequently 15 again inserted in said chamber and connected to its lid.

I claim as my invention:—

1. A furnace of the character specified comprising an open-bottomed cooling chamber; a charging chamber and a heating chamber located beneath the cooling chamber and communicating directly therewith; a series of frames adapted to contain the metal to be treated; a cover rotatably 25 mounted upon said cooling chamber; individual connections between each frame and

said cover, whereby the frames will be caused to travel in a circular path through the cooling chamber when the cover is rotated; and means for lowering or raising 35 said connections, to move said frames from said cooling chamber into and out of said charging and heating chambers.

2. A furnace of the character specified comprising an open-bottomed cooling chamber; a charging chamber and a heating chamber located beneath the cooling chamber and communicating directly therewith; a series of frames adapted to contain the metal to be treated; a cover rotatably 40 mounted upon said cooling chamber; individual rack connections between each frame and the cover, whereby said frames will be caused to travel in a circular path through the cooling chamber when the cover is rotated; and individual driving means connected with the racks for lowering or raising 45 the same, to move the corresponding frames into and out of said charging and heating chambers.

In testimony whereof I have hereunto set my hand in presence of two subscribing witnesses.

CARL KUGEL.
